JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

APPARATUS AND METHOD OF CHARGING A RETORT

Application filed September 25, 1928. Serial No. 137,708.

This invention comprehends improvements of general utility in the coking retort and kindred arts, and in its more specific aspects relates to improvements in retorts of the vertical type and more particularly to those of the "continuous" vertical type as exemplified, for instance, in my application—Serial No. 684,342, filed January 4, 1924, and has for an object the provision of means for efficiently transferring the material to be coked from a source of supply to the coking chambers of a battery of retorts.

This application is a continuation in part of my application Serial No. 40,068, filed June 27, 1925.

Where a continuous vertical retort battery comprises retorts and heating wall units separated by wall structure of considerable thickness the problem of providing charging apparatus therefor with adequate supports is simplified since the supporting columns can be located within said separating walls, but where, as herein contemplated, such walls are dispensed with and a long battery of continuous vertical retorts comprising ovens and heating walls juxtaposed in alternation is employed the difficulties of charging are materially increased. An outer framework can not be used for their support because not only is the top of such a battery very high but the bins would have to be elevated considerably above the top to provide the head room essential for operating a battery of this type, and this would necessitate the use of diagonal wind bracing between the sides of the supporting framework but the arrangement of ovens and heating walls indicated precludes the use of bracing of this type. Moreover, the fire hazards incident to the location of storage bins above such retorts is an additional important objection to their use.

Furthermore, in the charging of the continuous vertical retorts difficulties are met with when it is desired to alternate in succession charges of coarse coal with those of fine coal, respectively, in certain desired proportions, in order to facilitate the coking of the latter. Continuous retorts in order to effect uniform coking must be kept full at all times

and therefore require to be fed continuously. It is usual to feed a continuous retort from a bin containing the fuel to be coked, by means of a discharge pipe leading from the bin to the retort but this fails to provide for the feeding of different fuels successively into the retort and there is always present the liability of the flow in the discharge pipe to become retarded or stopped altogether and inspection to determine if the flow of fuel is uniform is impossible by this method.

My invention involves, broadly, the idea of practical means for overcoming all of these obstacles whereby a vertical retort battery and more particularly one of the continuous type, without regard to its length or height, may be efficiently equipped with charging apparatus. In the more specific aspects of my invention, I provide a charging larry car and a trackway therefor, the trackway being preferably supported on a framework independent of the brickwork and preferably above stationary charging hoppers for the several retorts, said charging hoppers being in turn preferably elevated above the normal level of the brickwork. The larry car is preferably provided with a hopper adapted to receive the coal from the storage bin and discharge the same into the respective feed hoppers, the larry car hopper preferably extending below the body of the car and between and to a point below the tracks so that when it is in alignment with a stationary feed hopper a clear view of their relationship is afforded. The larry car is also preferably provided with weighing mechanism of known construction. Inspection may be further facilitated by the provision of an operator's platform on the larry car likewise extending below the car body and between and below the rails in proximity to the larry car hopper. To further facilitate inspection of the discharging operations the lower end of the larry car hopper is offset and in order to prevent spillage of the fuel is provided with a pipe which may be dropped to span the space between said larry car and said stationary feed hopper. This pipe is preferably adapted to be extended to a point in the feed opening sufficiently low to permit, when removed, the

closing of the feed opening without obstruction by the material in said opening and a valve is also preferably provided between the hopper body proper and said pipe to control the flow of material to the latter.

As a further specific aspect of my invention, a storage bin or a plurality of storage bins, preferably supported independently of the battery brickwork, and preferably separated from the battery structure proper are employed. This removes the bin or bins from fire hazards and enables their supporting structure to be adequately braced against wind pressure and other disturbing forces which is desirable because of the great height to which they must be built.

By my invention I have solved the problem of continuously feeding a retort or retorts with different fuels of the exact proportions desired, for the larry car is adapted to be charged successively from the respective bins and, through the instrumentality of the weighing mechanism thereon, to deliver weighed quantities of each charge to the respective stationary hoppers, the several charges being superimposed therein, these hoppers while charged intermittently serving as reservoirs to deliver continuously to the retort chamber a mixture of the desired proportions. Since all operations are open to observation they can be closely inspected and any error incident thereto corrected.

In addition to the general features and objects of the invention above recited, the invention has such other improvements or advantages in construction and operation as are found to obtain in the structure and devices hereinafter described or claimed.

In the accompanying drawings, forming a part of this specification, and showing for purposes of exemplification, a preferred form and manner in which the invention may be embodied and practiced, but without limiting the claimed invention specifically to such illustrative instance or instances:

Figure 1 is a vertical longitudinal section on the line 1—1 of Fig. 2, showing a portion of a continuous vertical retort battery and storage bins and supporting structure therefor, the two structures being connected by a trackway on which a larry car is adapted to travel carrying with it a fuel conveying hopper.

Fig. 2 is a vertical transverse section through the battery, showing the relationship between the coking chambers, stationary feed hoppers, larry car charging device, and rails and supporting structures for the same, and

Fig. 3 is a detail sectional view of the lower end of the larry car hopper showing a pipe adapted to be lowered to bridge the space between said hopper and the stationary charging hopper.

The same characters of reference indicate

the same parts in each of the several views of the drawings.

Referring to Fig. 1 of the drawings, there is shown a supporting structure or tower 1 having near its top storage bins 2 which are adapted to be filled with fuels of different character, respectively, by suitable transfer means from a main source of supply, such, for example, as a barge or freight car. The top portion of a vertical retort is shown at 3 having coking chambers 4 separated by heating walls 5, said chambers being provided at their tops with stationary charging hoppers 6 rising above the top of the brickwork and adapted to be substantially filled with the fuel and to deliver the same continuously to the coking chambers. A supporting framework on the exterior of the brickwork is shown at 7 which framework may carry at its top a superstructure or housing 8 adapted to support the trolley conductors 9 and a trackway 10, the rails of which are separated by a free space longitudinally of the battery and above the stationary feed hoppers. A larry car 15, provided with a fuel conveying hopper 16 having at its lower extremity an offset discharge valve mechanism 17 and provided with weighing mechanism 14 of known construction, is adapted to travel on the trackway. The discharge end of the larry car hopper extends below the body of the larry car proper and through the space between the rails so that when the lower offset end of the hopper is in vertical alignment with a stationary hopper the discharge outlet of the former will be over the charging opening of the latter. Said larry car is also provided with an operator's platform 25 likewise extending through said space between the rails in proximity to the lower end of the larry car hopper. The valve mechanism comprises a pipe 18 with its upper side portion cut away at 19 as shown in Fig. 3, said pipe being adapted to slide in the guide portion 20 of the car hopper and to be substantially balanced in raised or lowered position by the lever 21, counterweighted at 22. A fuel valve 23 operated by lever mechanism 24 controls the flow of fuel from the car hopper. When the valve 23 is opened and the pipe 18 lowered the cut away portion 19 of the latter permits flow of the fuel from the car hopper 16 to the charging hopper 6 while the pipe bridges the space between said hoppers and thereby prevents spillage of the fuel.

In the operation of the device, when it is desired to charge the stationary hoppers, the larry car is run to a position beneath a storage bin and charged with fuel, its capacity being sufficient to enable it to charge a plurality of ovens. The car 15 is then run to a position with the discharge valve 17 vertically above the stationary charging hopper 6 which it is desired to charge. The anti-

spillage pipe 18 is then dropped into position to bridge the space between the car hopper extension and the feed opening in the stationary hopper, extending downwardly into the latter, the pipe being maintained in the adjusted position by the counterweight 22. The valve 23 is then opened and a weighted quantity of the material flows from the hopper, through the pipe and into the stationary charging hopper. The operator, from his position on the platform, may observe the proper alignment of the parts as well as the feeding operation. By the arrangement disclosed the spillage of fuel is rendered impossible since when the stationary hopper is filled the downward flow of fuel will stop inasmuch as it passes through a passageway entirely closed laterally by the sides of the hopper and the inter-connecting pipe. When the charging operation is completed the valve is closed and the pipe lifted. During the charging operations the material always settles to a point sufficiently below the top of the feed opening in the stationary hopper to permit the cover to be placed thereon. This results from the fact that in the charging position the end of the pipe extends substantially below the top of the feed opening, leaving a space above the lower end of the pipe sufficient to accommodate the charge remaining in the pipe after the valve is closed. After the charging operation is completed the larry car is free to move on to the next stationary hopper to be charged, and similarly for the remainder of the stationary hoppers. In like manner the several stationary hoppers may be charged in succession with weighed quantities of material from other of the bins, as found necessary to obtain the resultant charges desired.

The invention as hereinabove set forth is embodied in a particular form of construction, but may be variously embodied within the scope of the claims hereinafter made.

45. I claim:

1. In a continuous vertical coking apparatus, the combination with a battery of continuous vertical coking retorts; covered coal-feeding magazines mounted in the top of 50 and individual to the several coking chambers and adapted to feed coal continuously and gradually into the tops of said chambers; and a plurality of storage bins for 55 coals of respectively different physical character mounted above said battery at one end thereof; of a charging larry-car adapted to receive coals from each of said bins and shiftable from beneath the same and into 60 positions above and for connection with said magazines for severally recharging them and provided with weighing means for weighing the total quantity of coal received from 65 said bins by said car and for determining by weight the portions of the total quantity

delivered by said car to the respective magazines.

2. In a continuous vertical coking apparatus, the combination with a battery of continuous vertical coking retorts; covered 70 coal-feeding magazines mounted in the top of and individual to the several coking chambers and adapted to feed coal continuously and gradually into the tops of said chambers; and a plurality of storage bins for coals of respectively different physical character 75 mounted above said battery at one end thereof; of a charging larry-car adapted to receive coals from each of said bins and shiftable from beneath the same and into positions above and for connection with said magazines for severally recharging them and provided with measuring means for measuring the total quantity of coal received from said bins by said car and for measuring the 80 portions of the total quantity delivered by said car to the respective magazines.

3. In a continuous vertical coking apparatus, the combination with a battery of continuous vertical coking retorts; covered 85 coal-feeding magazines mounted in the top of and individual to the several coking chambers and adapted to feed coal continuously and gradually into the tops of said chambers; and a storage bin for coal mounted 90 above said battery at one end thereof; of a charging larry-car adapted to receive coal from said bin and shiftable from beneath the same and into positions above and for connection with said magazines for severally recharging them with a portion of the total quantity of coal in the larry-car and provided with weighing means and controlling 95 means for determining by weight and controlling the portions of the total quantity in 100 said larry-car delivered thereby to the respective magazines.

4. In a continuous vertical coking apparatus, the combination with a battery of continuous vertical coking chambers; covered 110 coal-feeding magazines mounted in the top of and individual to the several coking chambers and adapted to feed coal continuously and gradually into the tops of said chambers; and a storage bin for coal mounted 115 above said battery at one end thereof; and a charging larry-car adapted to receive coal from said bin and shiftable from beneath the same and into positions above and for connection with said magazines for severally recharging them with a portion of the total quantity of coal in the larry-car and provided with measuring means and controlling 120 means for measuring and controlling the portions of the total quantity in 125 said larry-car delivered thereby to the respective magazines.

5. The method of charging a battery of continuous vertical coking chambers, respectively provided at their tops with indi- 130

vidual reservoirs for continuous feed of coal to the tops of the several coking chambers, with coals of respectively different physical characteristics, from a plurality of storage bins by means of a larry car, which method
5 comprises: periodically recharging a plurality of the reservoirs of the battery of coking chambers one after another with coal during continuance of coking in said chambers;
10 effecting a succession of said periodic recharging operations with coals of respectively different physical characteristics successively; and delivering the respective kinds of coal to the several reservoirs, during the
15 period in the said succession of periods in which they are respectively being employed to recharge the reservoirs, by withdrawing a total quantity of the the respective coals sufficient to recharge a plurality of reservoirs and delivering a portion of the total withdrawn quantity to, and weighing the portion therefrom for, each of the said plurality of reservoirs severally.
20

In testimony whereof, I have hereunto set
25 my hand.

JOSEPH VAN ACKEREN.
